(57)

CLAIM

The ornamental design for a modular structure for audio-visual material, as shown and described.

DESCRIPTION

2. Modular structure for audio-visual material

2.1 : Front

2.2 : Back

2.3 : Bottom

2.4 : Top

2.5 : Left

2.6 : Right

2.7 : Perspective

The illustrated design refers to a structure with a horizontal support and a vertical wall. The illustrated design contains elements such as cabinet, audio-player device, screen, speakers which are shown in dotted lines for illustrative purpose only and do not form part of the claimed design.
